H. L. HARDY,

AUTOMATIC SELF CLOSING FLUSH VALVE FOR TOILETS.

APPLICATION FILED JULY 2, 1917.

1,297,563.

Patented Mar. 18, 1919.

FIG. 1.

UNITED STATES PATENT OFFICE.

HOMER L. HARDY, OF SPOKANE, WASHINGTON, ASSIGNOR OF ONE-HALF TO
H. G. DUERFELDT, OF SPOKANE, WASHINGTON.

AUTOMATIC SELF-CLOSING FLUSH-VALVE FOR TOILETS.

1,297,563.

Specification of Letters Patent. Patented Mar. 18, 1919.

Application filed July 2, 1917. Serial No. 178,257.

To all whom it may concern:

Be it known that I, HOMER L. HARDY, a citizen of the United States, residing at Spokane, in the county of Spokane and State of Washington, have invented new and useful Improvements in Automatic Self-Closing Flush-Valves for Toilets, of which the following is a specification.

This invention relates to improvements 10 in automatically closing flush valves which are specially designed for toilets.

My invention includes a valve mechanism having a valve closure which is manually operable against water pressure from the main in order to permit of ingress of the water to said mechanism, means being provided for positively retaining the valve closure in a full open position during the period of flush adjustment of the valve 20 mechanism.

A further feature consists in providing a timing reservoir in which a piston is controlled by water pressure for releasing the valve closure after a pre-determined period 25 of flushing, whereby the water pressure itself will close and seat said closure.

A further novel feature consists in automatically acting means for draining the timing reservoir after the valve closure has been seated, and in the preferred form, this automatic draining means is positively actuated upon movement of the valve closure to a seated position.

My invention includes a valve body which 35 has a discharge opening delivering to the bowl of the toilet which is very greatly restricted with respect to the area of the inlet to said body from the pressure main. Thus during the flushing inflow, a considerable 40 pressure of water will be maintained in the valve body and I utilize this pressure for discharge of a portion thereof into the timing reservoir to actuate the timing mechanism at the termination of a pre-determined period of flushing.

My invention has other objects and features which will be more fully described in connection with the accompanying drawing, and which will be more particularly 50 pointed out in and by the appended claims.

In the drawing:—

Figure 1 is a vertical sectional view of one form of the device of my invention showing the valve structure in a closed position.

Fig. 2 is a view similar to Fig. 1 showing the parts in an open position.

Fig. 3 is a sectional view on line 3—3 of Fig. 1.

Like characters of reference designate 60 similar parts throughout the different figures of the drawing.

As illustrated, 1 designates a hollow valve body which is adapted for direct connection with a pipe of a water main by means 65 of extension 2. A fitting 3 is turned into said extension 2 and is provided with a yoke 4 which constitutes a bearing for a closure stem 5 whereby the latter will be held to a linear path of movement. Said 70 body 1 has a partition 6 forming a valve chamber 7 through which the inflow passes under pressure toward and into said body 1. Said partition 6 is provided with a closure seat 8, as shown. A valve closure 9 is shown 75 formed integral with said stem 5 and said closure 9 is adapted to be manually operated or moved out of engagement with its seat 8, and toward and against the incoming pressure into an open position, as shown in Fig. 2. 80 Thus water pressure will always act to seat said closure. However, I have shown a spring 10 interposed between said closure and the bearing 4, which spring normally acts to supplement the water pressure, in seating 85 said closure, this spring being especially important when the mechanism is operated in connection with such a low pressure water system as four pounds to the square inch.

On a higher pressure, this spring is not so 90 important, as will hereinafter more fully appear. Extending from the closure 9 is a bifurcated stem portion 11, the latter terminating in a cylindrical stem portion 12. The cylindrical stem portion 12 is slidable 95 through a packing gland, indicated as a whole at 13 and is provided on its outer end with a push button 14 whereby the entire closure structure may be manually opened from the position shown in Fig. 1 to the 100 position shown in Fig. 2, against the action of spring 10 and the water pressure. The valve body 1 has a discharge opening 15 adapted to deliver to the bowl 16, of the 105 toilet, and the terminal end may be suitably equipped with any suitable form of nozzle-like device for rendering the discharge into the bowl as noiseless as possible, this feature not being a specific part of my invention.

However, a fan shaped terminal end might 110

be arranged to spread the flow against the interior wall of the bowl above the siphon level of the water.

It will now be seen that the valve seat 8 permits of inflow to the body 1 greatly in excess of the capacity of outlet 15 to discharge the water from said bowl the latter discharging against no resistance greater than atmospheric pressure. Thus there will be 10 some considerable pressure in the valve body 1 during the flushing operation.

I will next describe my improved automatically acting timing mechanism which is preferably operated by this pressure in 15 the valve body 1 to perform the function of terminating the flushing action at the end of a pre-determined period.

The upper end of the valve body 1 is open, as at 17, and is interiorly threaded. 20 A shoulder 18 is formed adjacent the top of said body. A cylindrical timing reservoir 19 has threaded connection with the valve body 1 and there is interposed between the reservoir casing 19 and the shoulder 18, a 25 diaphragm 20, which is rigid, and which divides the reservoir chamber from the hollow valve body 1. It will be understood that this timing reservoir is not designed to take the place of a flush tank and that it 30 does not function to hold a body of water for flushing the tank. On the other hand, the water that enters this reservoir is merely for the purpose of operating mechanism which I am now about to describe in detail.

35 A gasket 21 is interposed between the shoulder 18 and the reservoir 19. Said diaphragm 20 is provided with an opening 22 whereby the reservoir will constantly be in restricted timing communication with the 40 valve body for timing flow from the latter into the former. The upper end of said reservoir is provided with openings 23 to prevent air from pocketing in said reservoir and also to prevent vacuum interference 45 with a piston which I am about to describe.

I have shown a piston 24 provided with a disk gasket 25, the margin 26 of which engages the interior of the reservoir 19 to provide for a water-tight engagement. The 50 piston 24 is provided with a hub sleeve 27 which is externally threaded. A nut 28 is provided on said sleeve to hold the gasket firmly in position against the piston 24, the latter resting against the head 29, of said sleeve. Furthermore, said sleeve nut is threaded on a piston rod 29 which has a bearing at 30, in the top of the reservoir 19 and which also has a bearing 31, formed integral with the diaphragm 20. The bearing 31 is provided with a suitable packing gland 32 to prevent leakage around the piston rod from the valve body into the reservoir. A spring 33 is interposed between 60 said piston and the top of said reservoir to resist pressure movement of the piston in

the direction of the arrow shown in Fig. 2. Adjustment regarding the spring tension desired, may be effected by adjusting the piston on the threaded piston rod. The lower end of the piston rod 29 projects into the valve body and rests upon the top of the looped or bifurcated stem portion 11, as shown in Fig. 3, the terminal of said stem spanning the slot in said portion and being held down in position by spring 33. A retaining trip device is provided which may consist of a bell crank lever 34 which is pivoted at 35 in the slotted portion 11 and which has one arm 36 which is adapted to project above the stem. The terminal end 37 is adapted to rest against the piston rod 29, when in the position shown in Fig. 2, to retain the closure structure in an open position. A stop 38 limits movement of said trip device under the action of a leaf spring 39 which engages arm 40, of said lever 34, and which is secured at 41 to the stem portion 11. Thus when the closure structure is shifted from a closed to an open position, the piston rod 29 will depress the arm 36 until the end 37 reaches a position beyond the piston rod 29 whereupon the retaining device will take the position shown in Fig. 2 and the closure structure will then be locked or retained in a full open position. This adjustment will result in filling the valve body 1 under such pressure as to cause the water to pass up through opening 22 into reservoir 19 until the rising water level reaches the piston 24. Continued pressure 100 will overcome the spring 33 and will actuate the piston so as to elevate the piston rod out of engagement with the retaining end 37. This will free the closure structure for closing action by water pressure against 105 the closure 9, in addition to spring 10 and terminate flushing action. The period of flushing may not only be regulated by the size of opening 22, but it may additionally be regulated by adjustment of the piston 24 110 to either increase or decrease the tension of spring 33.

I will next describe the novel manner in which the controlling or timing reservoir mechanism is drained subsequent to each 115 flushing operation as otherwise the device would not be operative.

The diaphragm 20 is provided with a valve seat 42 for establishing communication between the valve body and the reservoir. A drain valve closure 43 is movable against the pressure in body 1 to close. A U-frame 44 is mounted upon the diaphragm 20 and the closure 43 is provided with a stem 45 which is slidable through said frame 44. A spring 46 is interposed between said frame and the closure 43 and normally acts to seat the latter. The lower end 47 of said stem extends into body 1 in the path of engagement of one arm 48 of a bell crank 130

lever. Said bell crank lever is pivoted at 49 to a hanger 50 and the remaining arm 51 being forked and straddling the slotted portion 11 of the closure structure. The forked 5 portion is provided with bifurcated limbs 52 adapted to engage trunnions 53, projecting laterally from the slotted portion 11.

It will now be clear that when the closure 10 is released and water pressure or the spring 10, or both, force the closure structure into the position shown in Fig. 1, the mechanism just described will open the drain valve or closure 43 at a time when pressure in the body 1 will have diminished so 15 that the contents of the timing reservoir may empty or drain by gravity into the chamber 1, and thence into the bowl 16. The arrow in Fig. 1 indicates the lower end 20 water level in the reservoir responsive to the draining action of the valve 43.

It will be noted that the drain valve is always open when the closure 9 is seated and therefore the reservoir will always be completely and quickly drained after each flushing 25 operation so that there will be no danger of freezing or interfering with a next and quickly following operation of the valve 9.

The spring applied to the closure structure will either be stronger than the spring 30 applied to the drain valve or there will be sufficient leverage to enable the combined pressure of the water and the closure spring to overcome the drain valve spring. Whereby the closure structure will be positively 35 closed and the quick drain valve positively opened. On low water pressure, the closure spring is usually desirable but on high water pressure, this spring can be eliminated.

It is believed that the novelty and utility 40 of my invention will be clearly understood from the foregoing description, and while I have herein shown and described one specific form of my invention, I do not wish to be limited thereto except for such limitations 45 as the claims may import.

I claim:—

1. In an automatic self-closing valve for toilets, a valve body for connection with a pressure main and including a valve seat and 50 a manually operable main valve closure structure for said seat, said valve body having a toilet flush outlet for discharge into the toilet bowl, a timing reservoir having restricted timing and direct communication 55 with said body for timing pressure inflow into said reservoir from said body, a spring controlled piston in said reservoir actuated by reservoir pressure and being operatively connected with said closure structure to hold 60 the same open after it is manually opened and releasing said closure structure upon actuation of said piston by timing pressure in said reservoir, an independently movable drain valve delivering directly from said 65 reservoir into said body independently of

said timing communication and being spring controlled to close against pressure in said body, and means actuated by closing movement of said closure structure for opening said drain valve against the action of said 70 spring to drain the contents of said reservoir directly into said body, substantially as described.

2. In an automatic self-closing flush valve for toilets, a valve body for connection with a pressure main and including a valve seat and a manually operable main valve closure structure for said seat, said valve body having a toilet flush outlet for discharge into said bowl, a timing reservoir having direct 80 restricted communication with said body for timing pressure inflow into said reservoir from said body, a spring controlled piston in said reservoir actuated by reservoir pressure against the said spring and being operatively connected with said closure structure to hold the same open after it has been manually opened and to release said closure structure upon actuation of said piston by timing pressure in said reservoir, and valve 85 means automatically and quickly draining said reservoir directly into said body independently of said restricted timing communication with said body after said closure structure has been seated, substantially as 90 described.

3. In an automatic self closing flush valve for toilets, a valve body for connection with a pressure main and including a valve seat and a manually operable valve closure structure for said seat, said valve body having a toilet flush outlet for free discharge into a toilet bowl under substantially atmospheric pressure, a timing reservoir having restricted 100 communication with said body for timing pressure inflow into said reservoir from said body, a spring controlled piston in said reservoir adapted to be actuated by reservoir pressure and being operatively connected with said closure structure to hold the same 105 open after it has been manually opened and to release said structure upon actuation of said piston by timing pressure in said reservoir, and means automatically and quickly draining said reservoir directly into said 110 body independently of said restricted timing communication and after said closure structure is seated, substantially as described.

4. In an automatic self closing flush valve, a valve body connected with a pressure main 120 and having a manually operable valve, a timing reservoir having timing and restricted open communication with said valve body, means in said reservoir for holding said valve open and adapted for actuation by 125 water inflow from said body to release said valve, a quick draining valve means spring controlled to close against water pressure in said valve body and delivering to said body directly independently of said restricted 130
